INVENTOR:
Carl Olson,
BY his ATTORNEY:
A. M. Carlsen.

UNITED STATES PATENT OFFICE.

CARL OLSON, OF RACINE, WISCONSIN.

RAIL-JOINT.

1,322,724.

Specification of Letters Patent. Patented Nov. 25, 1919.

Application filed April 28, 1919. Serial No. 293,351.

To all whom it may concern:

Be it known that I, CARL OLSON, a subject of the King of Sweden, who have declared my intention to become a citizen of the United States, residing at Racine, in the county of Racine and State of Wisconsin, have invented a new and useful Rail-Joint, of which the following is a specification.

10 My invention relates to railway rail joints, and the main object is to provide a strong, durable joint which can not accidentally become separated. A second object is to save material and labor in the 15 building and maintaining of a railway track, by eliminating all fish-plates, bolts and nuts from the joints.

In the accompanying drawing, Figure 1 is an end elevation of two rail sections 20 joined together by my new joint. Fig. 2 is a side view of what is shown in Fig. 1 but with portions of the rail sections broken away and some ties and spikes added. Fig. 3 is an end view of the base or joint piece 25 proper with the rail removed. Fig. 4 is a section on the line 4—4 in Fig. 3, and a portion of a rail section in dotted lines to indicate the position of the rail while it is being inserted or removed from the joint.

30 Fig. 5 is a side elevation of either one of the rail portions entering into the joint.

Referring to the drawing by reference numerals, 6 designates the base piece of the joint and may be cast of any suitable metal, 35 like gray-iron, malleable iron or cheap steel. It is formed with base flanges 7 abutting against the ends of the regular base flanges 8 of the rail sections 9, and 9^x, and is provided with two upstanding 40 integral, parallel wings 10 serving as fish-plates. These plates are preferably beveled at 11 and the space 12 between them corresponds to the thickness of the vertical web of the rails, and extends downwardly only 45 to the point or line 13, thus leaving the base thicker between than outside of the fish plates. Traversing said space is an integral cross bar 14 having its lower portion formed with inclines 15 and its upper side with less inclined faces 16. There 50 also project from the base into said space two lugs 17, each with two inclines, 18 and 19.

Each rail section has a portion of its 55 base flange 8 cut away as from A to B in Fig. 5, and with said flange a narrow strip

of the lower edge of the web 19 of the rail, as can be seen above the numeral 8 in Fig. 5. Said reduction of the web is to leave room for the portion of the base 7 projecting upward between the fish-plates 10. The remaining portion of the web is formed with a bottom notch 20 adapted to fit upon one of the lugs 17, and an end notch 21 adapted to fit upon one half of the cross 65 bar 14 when the parts are assembled.

In the operation or use of the invention, the parts are put together by tilting either the rail or the joining piece upwardly slightly out of line with each other and 70 pushing them together, then leaving such rail and joint piece on the ties 22, the next rail section is slightly tilted, as in dotted lines in Fig. 4, and inserted in the piece 6, and the next base piece, 6, put upon 75 the raised end of the section, and then that section is lowered down on the ties and the third rail section placed like 9^x in Fig. 4 and inserted, and so on, the sections and the joining pieces 6 are then secured to 80 the ties 22 by spikes 23 in the usual manner. To remove rails thus put down the process is simply a reversal of that just described for putting them down, so no further explanation is considered necessary. 85 If the new rail is to be joined to a rail laid and secured in the old way, by fish-plates and bolts, the remedy is simply to either make the adjacent end of the old rail like the rail piece in Fig. 5, or else join the new and 90 old rail together, in that particular place, by the earlier used fish plates and bolts, as it is a comparatively easy matter to cut one of the new rail sections square at the end and giving its web a couple of holes 95 for the regular bolts. And if a worn out or damaged rail section is to be replaced by a new one, the old section is cut in two intermediate its ends and removed, and a new section likewise cut is substituted and 100 the cut ends secured together by any suitable form of fish-plates and bolts.

When the parts are put together as shown in Fig. 2, it is evident that the bar 14 will prevent rising of the rail sections, and the lugs 17 will prevent longitudinal movement of the sections except the limited movement provided for in the parts to permit the track to contract and expand according to the atmospheric temperature.

It will be noted in Fig. 2 that there is one tie, 22, placed directly under the adja-

cent ends of the base flanges 7 and 8 to fully support the said parts, and if the base of the piece 6 is not made strong enough to be relied on as a bridge between said two ties, 5 then a tie may also be placed under the middle portion of the piece 6.

What I claim is:—

1. The combination with two adjoining ends of railway rails, of an integral joining piece adapted to receive and hold said ends in abutting position; said joining piece having base flanges corresponding to those on the rail, and two upstanding parallel plates with an intervening space to fit the 10 vertical web of the rails, two lugs projecting upwardly from the base of the joining piece a short distance into the space one near each end thereof, and an integral cross bar connecting the upper middle portions of the 15 plates; said rail ends having each a portion of the base flange removed and the adjacent lower edge of the rail web formed with a notch adapted to fit over the adjacent lug of the joining piece, and the end of said 20 web provided with a notch adapted to receive about half of the cross bar uniting the parallel plates.

2. The structure specified in claim 1, said notches in the webs of the rails being flared 25 so as to be more readily engaged with and

disengaged from the said lugs and bar, and the latter elements being shaped to fit loosely in said notches.

3. The structure specified in claim 2, said notches, lugs and cross bar being so arranged that they can not be disengaged as long as the joining piece and the rail sections remain in approximately rectilinear position or relation. 35

4. The structure specified in claim 1, and ties under the adjoining ends of the rail and the joining piece, and spikes holding the base flanges of said parts to the ties. 40

5. The structure specified in claim 4, and a tie supporting the middle portion of the 45 joining piece.

6. The structure specified in claim 1, the base of the joining piece being thicker between the vertical plates than outside of the same, and the web of the rail resting on 50 said thicker portion.

7. The structure specified in claim 6, and the tread of the rail having its lateral portions resting on the upper edges of said plates. 55

In testimony whereof I affix my signature.
CARL OLSON.
